CHECK HOLDING AND NOTCHING DEVICE
 Clinton E. Hicks, Cherry Hill, N.J., and John W. Zundt,
 Ardmore, Pa., assignors to Globe Ticket Company,
 Philadelphia, Pa., a corporation of Pennsylvania
 Filed July 1, 1963, Ser. No. 292,011
 1 Claim. (Cl. 225—89)

This invention relates to a check holding and notching device.

Checks in the form of slips or tickets bearing indicia are widely used where fares, fees or tolls are collected, the use being particularly widespread in the transportation and amusement field. Frequently the issuer of the check wishes to make a notch or opening adjacent a particular indicia to indicate for use at a later time information relative to the person to whom the check is issued. Typically the information thus indicated might be the destination for which a traveler has paid his fare or the fare zone in which the traveler entered a conveyance. Restaurants employ such systems, for example, to permit the waitress to indicate the amount which should be paid to the cashier. The wide use of such check systems is well known and hence need not be further detailed here.

The check holding and notching device of this invention is of particular value where the check issuer must be able to issue the check using only one hand. It is ideal for example, for a bus driver since it can be permanently mounted. With one hand the check issuer can adjust the device so that it will notch at the proper place and then remove the check properly notched.

The check holding and notching device of the invention is further advantageous in that it is not complex in construction and is inexpensive to produce.

The invention and its objects will be further clarified by a reading of the following description in conjunction with the drawings in which:

FIGURE 1 is a front elevation partially broken away of a check holding and notching device in accordance with the invention showing the device permanently mounted;

FIGURE 2 is a vertical section taken on the plane indicated by the line 2—2 in FIGURE 1;

FIGURE 3 is a plan view partially broken away of the device of FIGURE 1 taken on the plane indicated by the line 3—3 in FIGURE 2 and illustrating how a check is engaged by fingers so that it can be removed;

FIGURE 4 is a top plan view of an alternative check for use in the device of FIGURE 1; and

FIGURE 5 is a top plan view of a further alternative check for use in the device of FIGURE 1.

Referring now to FIGURES 1 and 2, a check holding and notching device 2 in accordance with the invention has a plate 4 which may, for example, be a metal and which forms a check support. Plate 4 is provided with opening 6 for the accommodation of machine screw 8 by which the device 2 is secured to a standard indicated at 10 which might, for example, be installed in a bus on the right hand side of the driver.

Plate 4 is provided with a pair of upstanding posts 12 which are squarely in cross section and are secured to plate 4, for example, by welding with each post positioned to have an inwardly facing corner 14. A plurality of checks 16 are stacked on plate 4 with each check 16 being provided with a notched opening 18 for the accommodation of each post 12 to thereby removably secure the checks to plate 4. Each check is marked off into a plurality of zones 19, each zone carrying appropriate printing 20 of indicators to indicate a different destination.

A stop 22 is struck up from plate 4 and has an outwardly turned corner portion indicated at 24.

A spring biased clamp 26 has a pair of levers 28 and 30 which are pivotally secured to a pin 32. A torsion spring 34 encompasses pin 32 and has a terminal arm 36 abutting against the interior of lever 30 and a terminal arm 38 which abuts against the interior of lever 28. Lever 30 has a jaw portion 39 for engaging the bottom surface of plate 4 while lever 28 has a jaw portion 40 for engaging the stacked checks 16. Jaw portion 40 has sharpened edges 41 and 42 where it overlies the stacked checks 16 and is provided with a V-shaped end 43. Portion 44 of lever 30 and portion 45 of lever 28 are adapted to be engaged by the user's fingers to move the jaw portions 39 and 40 apart against the force of spring 34.

A chain 46 has a terminal link 48 bolted to lever 30 as indicated at 50. A reduced neck portion 52 of lever 30 restrains link 54. A terminal link 56 at the other end of chain 46 is clamped to an opening 58 in portion 24 of stop 22.

It will be noted that checks 16 overlie the upper edge 62 of plate 4.

Operation

In operation with the clamp 26 removed, a stack of checks 16 are placed on plate 4 with openings 18 accommodating the posts 12. The check issuer then spreads jaws 39 and 40 by pressing on portions 44 and 45 of levers 28 and 30 placing jaw 39 below plate 4 and jaw 40 over the zone 19 of the upper most check which he wishes to notch. The clamp is then released and with the same hand the uppermost check is engaged by the index finger indicated at 64 and the thumb indicated at 66. The downward pressure of the index finger 64 causes the check to bow outwardly due to the stop action provided by stop 22. As the uppermost check 16 is pulled outwardly, it tears against the sharpened edges 41 and 42 of jaw portion 40 making a notch in the check at the oppositely designated place which may, for example, indicate the place of debarkation from a vehicle.

In order to issue the next check, the operator with the same hand can readily pull off another check if the destination of the next person is the same or, if it is not, readily replace clamp 26 with the same hand to the zone desired for the next person.

An alternative form of check is shown in FIGURE 4 wherein a check 68 is similar in all respects to check 16 but is provided with marked zones indicated at 72 containing printed destination zones indicated at 74. A typical notch 76 provided by the device of FIGURE 1 is illustrated.

Similarly, check 78 (FIGURE 5) similar in all respects to check 16, is provided with marked zones 80 containing printing monetary amounts indicated at 82. Such checks can be used, for example, to show an amount of money which is due, for example, for merchandise purchased.

What is claimed is:

1. In combination, a plurality of substantially rectangular check support members each having a rear face and a front face supporting said checks, a pair of retaining members secured to said support member and respectively passing through the openings in said check support members to releasably retain the checks on the support member; a clamp having a pair of opposed jaws and adapted to engage along a long side thereof the rear face of the check support member and the checks respectively;

spring urging the jaws towards each other, the jaw engaging the checks having a reduced end and sharp edges, hand hold means for moving the jaws apart to disengage the clamp from the checks and the rear face of the check support member, and a check stop member adjacent one end of the side of the support member engaged by the clamp and remote from the retaining members.
